Glidden Company, Cleveland, Ohio, a corpora-
tion of Ohio

No Drawing. Application February 10, 1944,
Serial No. 521,851

8 Claims. (Cl. 260—397.3)

1

The present invention relates to the degradation of bile acids and similar acids obtained by the oxidation degradation of steroids, and more particularly relates to an improvement in the Barbier-Wieland process for converting bisnor-
cholenic acid to progesterone.

With his discovery of 3-hydroxy bisnorcholenic acid from the plant sterol, Stigmasterol, Ann. 507 128 (1933), Fernholz immediately realized that a Barbier-Wieland degradation of this acid, Gilman, Organic Chem., vol. II, page 1357 (1943), followed by oxidation of the 3-hydroxy group, would lead to progesterone, Ber. 67 1855, 2027 (1934). Almost simultaneously Butenandt, whose brilliant work on the isolation of the corpus luteum hormone from natural sources had corroborated the earlier work of Allen and his co-workers, likewise saw the significance of Fernholz's discovery, Ber. 67 1611, 1901, 2085 (1934). Both of these workers almost simultaneously applied the Barbier-Wieland technique to Fernholz's acid. Butenandt apparently finishing and publishing his experiments a short time before those of Fernholz came into print.

Neither of these workers, however, departed essentially from the traditional Barbier-Wieland procedure nor did they improve upon this procedure in the case of the substances they were working with. Thus a total of at least seven distinct steps was involved in going from 3-acetoxy bisnorcholenic acid to progesterone. These steps may be outlined as follows:

Step 1.—Conversion of the acid into its methyl ester (via diazo-methane).

Step 2.—Conversion of the methyl ester to 3-hydroxy tertiobutenyl-diphenyl-carbinol.

Step 3.—Acetylation of the tertiobutenyl-di-
phenyl-carbinol and dehydration to the corresponding diphenyl-ethylene.

Step 4.—Ozonization of the diphenyl-ethylene to pregnenolone acetate.

Step 5.—Conversion of pregnenolone acetate into its semi-carbazone for isolation and purification.

Step 6.—Hydrolysis of the semi-carbazone to pure pregnenolone.

Step 7.—Oxidation of the 3-hydroxy group of pregnenolone to yield progesterone.

This embarrassing multiplicity of distinct operative steps, together with the relative inaccessibility of Stigmasterol, made a commercial exploitation of the Fernholz-Butenandt procedure for the preparation of progesterone impractical.

It is accordingly an object of the present inven-

2

tion to provide an improved process for producing progesterone.

A further object is to provide a simplified process of preparing progesterone from bisnorcholenic acid.

An additional object is to reduce greatly the number of steps involved in producing progesterone from bisnorcholenic acid.

Another object is to provide a new process for decomposing ozonides of the type

15 where R^1 and R^2 are hydrocarbon residues, and R^3 is a cyclopentano hydrophenanthrene nucleus, to the corresponding ketones.

A further object is to provide a new process for converting carbinols of the type

20 where R^1 and R^2 are hydrocarbon residues and R^3 is a cyclopentano hydrophenanthrene nucleus, into ketones of the formula

Other objects will be apparent to those skilled in the art from the following description.

In United States Patents Nos. 2,218,971, 35 2,273,045 and 2,273,046 there are disclosed procedures which make Stigmasterol readily accessible. In United States Patent No. 2,304,100 there is disclosed a method by which Step 1 of the Barbier-Wieland procedure outlined above was 40 eliminated, whereby the acid can be converted directly into the carbinol of Step 2 without going through the commercially difficult step of esterification with explosive diazo-methane.

In the present invention further improvements 45 in the procedure leading to the preparation of progesterone are obtained, and the process involves the complete elimination of Step 3 above, and the replacement of the remaining four steps by one operative procedure. Thus the seven 50 steps of the above procedure now become a two-step operation of great simplicity which yields a hormone of a high degree of purity and in greatly enhanced yields.

Briefly outlined a preferred mode of carrying 55 out the process comprises treating the carbinol

in glacial acetic acid with halogen, passing in ozone, adding an oxidizing agent such as chromic acid, then a dehalogenating agent—all carried out in one operation. In short the carbinol is dissolved in glacial acetic acid and, after addition of the reagents indicated above, and progesterone is isolated from the solution.

To effect this very simplified and time-saving procedure, certain novel chemical reactions had to be introduced. Thus vigorous ozonization of the free carbinol gave better yields of an ozonide than those obtained by ozonization of the diphenyl-ethylene such as is described in Step 4 above. To our knowledge this is the first time that a carbinol has been so directly converted into the ozonide of its corresponding ethylene and the invention comprises, inter alia, this method of treating tertiary carbinols of the type herein contemplated.

After addition of sufficient chromic acid to the ozonide to convert the 3-hydroxy group into the 3-keto group, a solution of chromous chloride is added. Instead of chromous chloride we have also been able to use quite successfully vanadous chloride or a 20% commercial solution of titanous chloride. Our yields are greatly enhanced by the smooth action of such highly reducing agents as chromous chloride in effecting clean cleavage of the ozonide as well as complete and smooth dehalogenation. This novel method of dehalogenating has in this case as well as in others proved to be a most useful tool and may be used for treating compounds of the general type contemplated herein.

Following the treatment of an acetic acid solution of 3-hydroxy ternal-cholenyl-carbinol by bromine, ozone, chromic acid, and chromous chloride, all in direct succession in the same reaction vessel, it is very easy to separate from the solution progesterone of a high degree of purity.

The following examples serve to illustrate the invention:

Example I

To a suspension of 30 grams of finely powdered 3-hydroxy Δ^5 -ternor-cholenyl-diphenyl-carbinol (recrystallized from chloroform) in 250 cc. glacial acetic acid is added at a room temperature a solution of 2.7 cc. (8.4) grams of bromine in 150 cc. of glacial acetic acid. The solution is warmed to 96–100° F. and an ozone-oxygen mixture containing 3 to 4% of ozone by volume passed in for 30 minutes at a rate of flow of 3.5 liters per minute. The dibromide of the carbinol usually crystallizes out of solution toward the end of the bromination time and the solution should be clear at the end of the ozonization. During the ozonization the temperature rises several degrees.

The solution after ozonization is cooled at once to 70° F. and the oxidizing mixture, cooled before using, and consisting of 10 grams chromic oxide, 1 cc. concentrated sulfuric acid, 15 cc. of water and 80 cc. glacial acetic acid, is added with stirring during several minutes, never allowing the temperature of the reaction mixture to rise above 80° F. After standing for 1 hour at room temperature, 20 cc. of methanol is added to the reaction mixture. The reaction mixture is now diluted with 500 cc. of glacial acetic acid and the resulting solution cooled to 60° F. 300 cc. of one molar chromous chloride solution, prepared according to the procedure of Conant and Cutter, J. A. C. S., 48 1023 (1926), is then added with shaking under an atmosphere of carbon dioxide. After standing for $\frac{1}{2}$ hour (or the solution may stand as long as over night, if desired), the solu-

tion is concentrated under the vacuum of a water pump and at 80 to 90° C. until 500 to 600 cc. of distillate have collected.

The reaction mixture is now diluted with 3 to 4 volumes of water and extracted four times with ether. The ether extractions are washed successively with water, 10% sodium hydroxide solution, and water again. The washed ether extracts are combined, concentrated and steam distilled. The residue from the steam distillation is cooled, taken up in ether and the ether extract again washed successively with water, dilute sodium hydroxide and water. The final ether solution is concentrated to a volume of about 20 cc. whereupon progesterone crystallizes out on cooling. The crude progesterone is filtered and washed with a cold petroleum ether mixture. The average yield is about 7.5 grams, M. P. 118 to 127° C. On again steam distilling, the mother liquors and working up as indicated above, 2 grams of a second crop of material, M. P. 116 to 121° C. may be obtained. The crude progesterone is purified by crystallization from acetone, yielding colorless prisms melting at 127 to 129° C.

25

Example II

The procedure was identical with that in Example I except that the chromous chloride was replaced by 300 cc. of a 1 molar solution of vanadous chloride prepared according to the method of Conant and Cutter, J. A. C. S., 48 1023 (1926), and the vanadous chloride was added to the mixture without dilution of the mixture prior to the addition of the debrominating agent. The crude progesterone had a melting point of 117 to 124° C.

35

Example III

The procedure was the same as in Example I except that 300 cc. of a commercial 20% solution of titanous chloride was used as the debrominating agent, and there was no dilution of the reaction mixture prior to the addition of the debrominating agent. The crude progesterone had a melting point of 117 to 124° C.

40

Example IV

The procedure was the same as in Example III, except that the reaction mixture was heated on a steam cone for one hour for the debromination. The crude progesterone had a melting point of 113 to 119° C.

45

Other oxidizing agents than chromic acid which are capable of converting the 3-OH group to a keto group may be employed, such as chromates and permanganates. In certain phases of the invention the nuclear double bond may also be protected by the use of other known removable reagents such as hydrobromides, etc.

The method for decomposing ozonides and dehalogenation by the use of the chromous, vanadous and titanous salts, which method is a significant feature of this invention, is also applicable where the 3-OH group is not oxidized to the 3-keto group. Thus the series of steps outlined above for the preparation of progesterone may be altered in that after bromination and ozonization the resulting ozonide is treated directly with the chromous, vanadous or titanous salts to yield pregnen-5-3-ol-20-one. Obviously this procedure is applicable where the starting material contains a 3-acyloxy group.

The process of the present invention may be

55

60

65

70

5

employed with other carbinols than the diphenyl carbinol. In general any carbinol of the formula

which upon dehydration forms ethylenes of the type

in which R is hydrogen or a hydrocarbon radical may be used.

Reference is made to copending application Serial No. 521,850 filed concurrently herewith, now Patent No. 2,374,683.

Having described the invention what is claimed is:

1. The process which comprises the steps of first treating 3-hydroxy Δ^5 -ternorchoenyl diphenyl carbinol with bromine, ozonizing the brominated material, converting the 3-hydroxy group of the ozonization product to a keto group, treating the resulting 3-keto compound with a dehalogenating agent, all without isolation of intermediates, and recovering progesterone from the reaction mixture.

2. The process of claim 1 in which the dehalogenating agent is chromous chloride.

3. The process of claim 1 in which the dehalogenating agent is vanadous chloride.

4. The process of claim 1 in which the dehalogenating agent is titanous chloride.

6

5. The process of producing progesterone which comprises successively treating a solution of 3-hydroxy Δ^5 -ternorchoenyl-diphenyl carbinol in acetic acid with bromine, ozone, chromic acid, and chromous chloride, without isolation of intermediates, and recovering progesterone from the reaction mixture.

6. The method of converting ter-nor-cholenyl carbinols of the formula

10

wherein R represents phenyl radicals, and R' is an etio-cholenyl radical, into ketones of the formula

20

which comprises subjecting said carbinols to the action of first bromine and then ozone, and decomposing the ozonide with a reducing agent.

7. The process which comprises successively treating 3-hydroxy Δ^5 ternorchoenyl diphenyl carbinol with bromine and then treating the bromination product with ozone.

8. The process of producing progesterone which comprises successively treating a solution of 3-hydroxy Δ^5 ternorchoenyl diphenyl carbinol with bromine, ozone, chromic acid, and a debrominating agent, without isolation of intermediates and recovering progesterone from the reaction mixture.
